[57] CLAIM

The ornamental design for a wall mounted support, substantially as shown and described.

DESCRIPTION

FIG. 1 is a front elevational view of a wall mounted support showing my new design;

FIG. 2 is a front perspective view thereof;

FIG. 3 is a top, plan view thereof;

FIG. 4 is a side elevational view thereof;

FIG. 5 is a rear elevational view thereof; and

FIG. 6 is a cross-sectional view taken along line 6—6 of FIG. 5.
